METHOD OF HEAT TREATING METALS

Charles O. Burgess, New York, N. Y., assignor, by
mesne assignments, to Union Carbide and Car-
bon Corporation, a corporation of New York

Application May 4, 1933, Serial No. 669,292

15 Claims. (Cl. 148—21)

This invention relates to methods of heat treating metals. More particularly this invention relates to an improved method of forming a case hardened surface on steel and alloy crank-shafts and on other cylindrical, conical or similar objects, such as shafting and trunnions.

Numerous methods have been devised for producing hardened surfaces on various steel and alloy objects such as shafting, valves, wheels, rails, gear teeth and other metal parts subject to severe wear. The early method of rotating the object and heating at one point on the surface while simultaneously quenching at a point on the heated area has not been found to be entirely satisfactory on account of the annealing effect which occurs where the heating flame completes the end of one revolution of the object and overlaps onto the area that has been quenched and previously hardened. Even with careful manipulation of the heating flame a joint or line of softer material appears where the annealing takes place and a narrow axial annealed zone is the result.

Some of the disadvantages of these prior methods have been overcome by the process disclosed in Patent No. 1,759,603 in which valves are case hardened while rapidly rotating in the chuck of a drill press, the heat being supplied by an oxy-acetylene blowpipe or an electric arc and quenching being accomplished by lowering the valve into a bath. Patent No. 1,536,416 also discloses a method of heat treating an object by directing a flame against the periphery during rotation and by cooling in the open air. However the "case" or layer of hardened surface metal resulting from these methods and other methods previously known has not been entirely uniform.

An object of this invention is therefore to provide a method for producing a uniform, case hardened surface on cylindrical, conical or other similar metallic bodies. Another object of this invention is to provide a method for producing a uniformly hard surface on the trunnions of crankshafts. These objects and others together with the novel features of this invention will be apparent from the following description and the accompanying drawings, of which

Fig. 1 is a view of a crankshaft as set up in a lathe in position for heat treatment;

Fig. 2 is a view of one form of apparatus adapted to carry out the method of this invention;

Figs. 3, 4, 5, and 6 are end views of the blowpipe shown in Fig. 2;

Fig. 7 is a view of another form of blowpipe

apparatus also adapted to carry out the method of this invention;

Figs. 8, 9, 10, 11, 12, 13, 14, 15, 16, and 17 are end views of the blowpipe apparatus shown in Fig. 7; and

Fig. 18 is a side view of the blowpipe apparatus shown in one operating position relative to a cylindrical object.

In accordance with this invention an object to be heat treated, such as a crankshaft C may be set up in a lathe A or in similar apparatus adapted to rotate the object. A blowpipe B is employed to raise the temperature of the object C to the critical range for hardening while being held in any suitable manner at a short distance from the surface to be heat treated.

During the preliminary heating of the object C to the critical range of temperature preparatory to sudden quenching, the speed of rotation of the object C may be regulated so as to obtain uniform heating of the entire surface exposed to the blowpipe flame or flames. With the majority of carbon steels and alloy steels it has been found that a speed of 120 R. P. M. is a satisfactory rate of revolution during both heating and quenching, but other speeds may be employed. When the speed of rotation is sufficiently great there will be no significant temperature difference between any two circumferentially separated points on the surface of the object. Heat is applied long enough to obtain the required surface temperature and depth of hardening. The surface hardness and depth of hardness may be varied at will by regulating the quantity and rate of heat application, as by using different sizes of flames or a multiplicity of flames. When the proper surface temperature or hardening temperature has been reached, the blowpipes or sources of heat are removed and immediately a fluid quenching medium is applied to the surface of the rotating object, thus obtaining uniform quenching conditions around the periphery of the object.

The preferred method of quenching is by means of a jet of water having an appreciable velocity head for breaking through any protecting steam envelope which may form around the object during the quenching action. An effective and thorough cooling of the object may be thus obtained so that the hardened area is substantially of the same measured renitence at all points around the periphery. When water or other suitable quenching medium is directed under pressure against the object to be hardened, the quench occurs immediately and nearly simulta-

neously over the entire area under treatment as the object is maintained in rotative movement.

The depth of the hardened surface, or the so-called "case", may be varied by changing the length of the interval of subjecting the object to heat after the critical temperature of the metal has been reached. On longer application of heat to the surface the temperature is raised beyond the critical point to a considerable depth beneath the surface of the object, and when the object is quenched, the sudden chilling causes hardening to the desired depth.

As disclosed and claimed in my copending divisional application, Serial No. 104,660, filed October 8, 1936, a blowpipe has been devised which is especially adaptable to the case hardening of cylindrical or conical objects, such as shafting or the journals and bearing surfaces of crankshafts. Such a blowpipe may comprise a head 20, as shown in Fig. 2, for receiving mixed combustible gases and for delivering these gases to a plurality of tips or nozzles 21 supported in the head. The nozzles 21 are readily removable from the head and, as shown in Figs. 4, 5, and 6, plugs 22 may be substituted for certain of the nozzles, depending on the shape of the object to be heat treated.

Where the object to be hardened has free ends, as a short shafting, or roller bearing, all of the nozzles 21 are preferably left in the head 20 with the exception of those in the four corners, which are removed and replaced by plugs 22 as shown in Fig. 3. A full sheet of flame will thus be produced which has slightly less intensity at the ends than at the center in order to offset the effect of conductance at the center area of the bearing, where heat is dispersed into the body of the bearing more rapidly than at the ends. In the case of small objects, such as short roller bearings, additional nozzles are blocked off, as shown in Fig. 4, so that more heat is directed against the central area than at the ends. When the temperature is raised substantially equally at all points of the object being heat treated, the hardened area produced by quenching will be uniformly renitent.

The trunnions of crankshafts are bordered at each end by cheeks, and for that reason are best heat treated by applying more heat near the ends than at the center. The nozzles of the blowpipe 20 are blocked off, as in Fig. 5, leaving a row of tips at each end and a single row laterally across the face of the blowpipe. The additional heat supplied at the ends of the trunnion is absorbed by the cheeks of the crankshafts so that the surface of the trunnion is brought to the critical range of temperature at all points of the surface. In hardening the ends of bodies having surfaces of rotation, such as shafting, an arrangement of tips, as shown in Fig. 6, may be made whereby nozzles are plugged off at the end of the blowpipe which is adapted to direct flames to the free end of the shafting.

As further disclosed and claimed in my copending divisional application, a blowpipe may be employed which comprises a multi-unit head, as shown in Fig. 7. Any convenient number of gas distributing heads 30, preferably three, may be assembled in close relation with one another, being adjustably supported by a block 31. Each head has one or more outlets into which are screwed or otherwise secured a corresponding number of blowpipe nozzles 32. Gas conducting and water cooling conduits 37 and 38 respectively are connected with each of the heads 30

and are shielded by larger conduits 33 which lead through a slot 34 in the block 31. In order to allow the heads 30 to be positioned in various arrangements for heating objects of different shape, the conduits 33 are movable sideways along the slot 34 and vertically through the slot. Nuts 35 and 36 threadedly engage the conduits 33 and lock the conduits against the block 31 when the desired arrangement of the heating heads 30 has been obtained.

Any one, two or all three of the heads 30 may be used in heating objects to be case hardened. An arrangement of the heads with two withdrawn and the gas supply to these heads shut off as shown in Fig. 8, is suitable for heating objects of short altitude or of small diameter. Objects having greater diameters may be heated by two or three of the heads, as shown in Figs. 9 and 10, and objects of greater length may be best heated by two or three of the heads arranged end to end, as in Figs. 11 and 12. When only one end of the object to be heat treated is free and the other end is attached, the heads may be arranged, as in Fig. 13, 14, or 15, with one or two of the heads at right angles to the object. If the object is free at the ends and attached at the middle, the center head only may be positioned at a right angle to the work, as shown in Fig. 16, and if both the ends are attached, then the heads at each end may be arranged at right angles to the work, as shown in Fig. 17.

The heads 30 of the adjustable apparatus may be arranged in any convenient manner with respect to the axis of the object to be heated. However for treating cylindrical objects, as shown in Fig. 18, the heads 30 are preferably aligned parallel with the axis of the object and the center head is retracted for a short distance so that heat of equal intensity is produced on the surface of the object by the jets from all three of the heads. The center head may be adjusted to conform with larger or smaller radii of differently sized objects, and the distance between the nozzles of the heads and the surface of the object may be maintained so as to effectively utilize the heat produced.

It will be appreciated that the multi-unit blowpipe is adaptable to heat objects of many different sizes and lengths by changing the arrangement of the nozzle-bearing heads. Such changes are readily effected by loosening the nuts 35 and 36 and by moving the conduits 33 to changed positions with respect to the block 31.

Although more than one embodiment of this invention has been described and illustrated, it should be understood that other changes may be made without departing from the scope of this invention.

I claim:

1. A method of heat treating a trunnion between cheeks of a crankshaft which comprises rotating the crankshaft, applying high temperature heat to the trunnion, said high temperature heat being of greater intensity adjacent said cheeks whereby the temperature of the trunnion is raised uniformly along the surface thereof; and quenching the heated surface while still rotating by directing an impacting jet of cooling medium against said trunnion, said jet having a velocity such that the formation of a quench-retarding envelope of steam around said object is avoided.

2. A method of heat treating a roller bearing which comprises rotating the bearing; applying a varying source of high temperature heat to the

surface of the bearing, said high temperature heat being of greater intensity at the middle portion of the bearing where heat is conducted away most rapidly; raising the temperature of the surface of the bearing uniformly to the critical range; and quenching the heated surface while still rotating by directing a jet of cooling medium against said bearing.

3. A method of heat treating the end portion of an object having a surface of rotation which comprises rotating the object about the axis of said surface; applying a varying source of high temperature heat to the surface of the object at said end portion, said high temperature heat being of less intensity toward the free end and of greater intensity toward the attached end of the portion under treatment; raising the temperature of the surface of the object at the end portion uniformly to the critical range; and quenching the heated surface while still rotating by directing a jet of cooling medium thereon.

4. A method of heat treating a metallic body of which the cross-section is circular but the outline is irregular which comprises rotating said body about its axis at a relatively high speed, uniformly heating the surface of said body to the required temperature and depth by applying thereto during rotation a heat source of which the shape and intensity are such as to fit and compensate for differences in heat conductivity of various portions of said body due to the irregular outline thereof, and thereafter quenching said body.

5. The method of heat treating a metallic body of a circular diametrically varying cross-section which comprises the steps of rotating said body about its axis, heating simultaneously each longitudinal portion of the surface of said body by applying thereto a heat source varying in intensity in accordance with the heat conducting properties of each of said portions so as to heat the entire surface of said body uniformly to the desired temperature, and thereafter quenching such heated surfaces during continued rotation of said body.

6. The method of heat treating the end portion of a circular body which comprises the steps of rotating said body about its axis, heating simultaneously each longitudinal portion of the surface of said end portion by applying thereto a heat source varying in intensity in accordance with the heat conducting properties of each of said portions so as to heat the entire surface to be treated uniformly to the desired temperature, and thereafter quenching such heated portions during continued rotation of said body.

7. A method of hardening a surface of a metallic body, which comprises applying high temperature heat to said surface while rotating said body at a relatively high speed to rapidly move said surface relatively to the high temperature heating means; discontinuing the application of such heat when said surface has been heated to a predetermined high temperature; and thereupon, and while said body continues to rotate, directing a jet of cooling fluid against such heated surface to quench the same.

8. A method of hardening a surface of a metallic body, which comprises applying high temperature heat to said surface while rotating said body at a relatively high speed to rapidly move said surface relatively to the high temperature heating means; discontinuing the application of such heat when said surface has been heated to a predetermined high temperature; and there-

upon, and while said body continues to rotate, quenching such heated surface by directing against the same a cooling water jet of sufficient velocity to break through any steam envelope which may form on said surface during such quenching.

9. A method of substantially uniformly hardening a surface of a metallic body having portions differing in their capacity to hold heat, such method comprising applying high temperature heat to said surface while rotating said body at a relatively high speed to rapidly move said surface relatively to the high temperature heating means; so adjusting the amount of heat applied by such heating means relatively to the differing heat-holding capacity of said body that said surface is substantially uniformly heated to a predetermined high temperature; discontinuing the application of such heat when said surface has been heated to such predetermined temperature; and thereupon, and while said body continues to rotate, directing a jet of cooling fluid against such heated surface to quench the same.

10. A method of substantially uniformly hardening a surface of a metallic body having portions differing in their capacity to hold heat, such method comprising applying high temperature heat from a localized source to said surface while rotating said body at a relatively high speed to rapidly move said surface relatively to such source of high temperature heat; so adjusting said source that the amount of heat applied thereby relatively to the differing heat-holding capacity of said body will be such that said surface will be substantially uniformly heated to a predetermined high temperature; discontinuing the application of such heat when said surface has been heated to such predetermined temperature; and thereupon, and while continuing such rotation of said body, quenching such heated surface by directing against the same a cooling water jet of sufficient velocity to break through any quench-retarding steam envelope that may form on said surface during such quenching.

11. A method of hardening a surface of a metallic body having a portion adjacent a boundary of said surface which will tend to cause heat to be removed at a faster rate by conduction from such boundary than from the central part of said surface, such method comprising applying a high temperature heating medium directly to said surface and in such a manner as to concentrate heat at such boundary so that the entire surface to be hardened will be heated uniformly to a temperature at or above the critical range and flow of heat by conduction to the portion adjacent the boundary will be compensated for; discontinuing the application of said heating medium; and subsequently cooling said surface so as to harden the same.

12. A method of heat treating a trunnion between cheeks of a crankshaft, said cheeks tending to remove heat by conduction at a faster rate from the ends of the surface of said trunnion than the rate at which heat is conducted from the remainder of the surface of said trunnion, such method comprising applying a source of high temperature heat to said trunnion, said high temperature source of heat being adapted to supply a greater amount of heat to one portion of the surface of said trunnion than to another; so adjusting the amount of heat applied by said source so as to apply a greater amount of heat adjacent said cheeks in order that the conduction of heat into said cheeks will be compensated for and the

- entire surface of said trunnion will be heated uniformly to a temperature at or above the critical range; and cooling the heated surface at a rate sufficient to harden the same.
- 5 13. A metal crankshaft having a trunnion thereof provided with a uniformly hardened surface portion, said trunnion being bordered by cheeks, and said uniformly hardened surface portion extending from cheek to cheek, and also extending to a uniform depth at all points from cheek to cheek, said trunnion having an interior composed of tough unhardened metal having the same chemical composition as said hardened surface portion.
- 10 14. A method of substantially uniformly hardening a surface of a metallic body having portions differing in their heat-holding capacity and a portion adjacent a boundary of said surface which will tend to cause heat to be removed at a faster rate by conduction from such boundary than from the central part of said surface, such method comprising applying a high temperature heating medium directly to said surface so as to concentrate heat at such boundary and in such a manner relatively to the differing heat-holding capacities of said portions so as to heat said surface uniformly to a predetermined high temperature; moving said surface and said high temperature heating medium relatively with respect to each 15 other at a relatively rapid rate and in such a man-
- 20
- 25
- 30

ner that said surface is traversed by said heating medium a plurality of times; discontinuing the application of said heating medium; and subsequently cooling said surface so as to harden the same.

5 15. A method of substantially uniformly hardening a surface of a metallic body having portions differing in their heat-holding capacity in one direction of said surface, such portions including a portion adjacent a boundary of said surface which will tend to cause heat to be removed at a faster rate by conduction from such boundary than from the central part of said surface, such method comprising applying a high temperature heating medium directly to said surface in 10 such a manner as to concentrate heat at said boundary and also in such a manner relatively to the differing heat-holding capacities of said portions so as to compensate for the differences in heat conduction; effecting a relative movement 15 between said heating medium and said surface in a direction substantially transversely to said first-mentioned direction and in such a manner that said surface is traversed by said heating medium a plurality of times; discontinuing the 20 application of said heating medium; and subsequently cooling said surface so as to harden the same.

CHARLES O. BURGESS. 30
